Primary Examiner — Leanne Was-Englehart

(74) Attorney, Agent, or Firm — Tucker Ellis LLP

(57) **CLAIM**

The ornamental design for a cover, as shown and described.

DESCRIPTION

FIG. 1 is a perspective view of a cover showing our new design;

FIG. 2 is a front view thereof;

FIG. 3 is a rear view thereof;

FIG. 4 is a top view thereof;

FIG. 5 is a bottom view thereof;

FIG. 6 is a left side view thereof; and,

FIG. 7 is a right side view thereof.

The broken lines depict portions of the cover that form no part of the claimed design.
